UNITED STATES PATENT OFFICE.

JOHN P. CUNNINGHAM, OF MILWAUKEE, WISCONSIN.

CLOTHESLINE HOLDER.

Application filed January 3, 1922. Serial No. 526,697.

To all whom it may concern:

Be it known that I, JOHN P. CUNNINGHAM, a citizen of the United States, residing at the city of Milwaukee, in the county of Milwaukee and State of Wisconsin, have invented a new and useful Clothesline Holder, of which the following is a specification.

My invention relates to improvements in clothes line holders which have upwardly extending, bifurcated projections or prongs about which a clothes line may be hitched and tightened with a minimum of effort, without any knots being necessary in any part of the clothes line, and which may be conveniently and securely fastened to the side of a building, post, tree, upright, or such other supporting means, and also, conveniently removed therefrom.

20 I attain these objects by the device illustrated in the accompanying drawing, in which—

Figure 1 is a perspective view of a wrought holder showing a portion of rope secured thereon; Figure 2 is a front elevation view and Figure 3 is a side elevation view of the same holder; Figure 4 is a front elevation view of the holder adapted to casting, and Figure 5 is a side elevation view 30 of such adaptation.

Similar letters refer to similar parts throughout these several views.

The part, *a*, of the holder allows of wood screws or bolts being passed through the 35 opening, or openings, *o*, therein. The heads of the screws or bolts are tightened against the outer surface, *b*, when the holder is secured, by means of the screws or bolts to the upright, designated as *A*. The shank 40 or stem, *c*, extends at right angles, or preferably, at a trifle less than at right angles to the plane of said surface, *b*, a convenient distance therefrom. At the outermost end of said stem or shank, *c*, the two prongs or 45 projections, *d*, bifurcate upwardly and somewhat inwardly toward the plane of said surface, *b*, in the shape of the letter V. In the wrought form of construction, illustrated in Figures 1, 2 and 3 of the drawing, the tops 50 of these two prongs or projections, *d*, may be brought closer together in case a thinner rope is to be fastened upon the holder, or said prongs or projections may be further separated in case a thicker rope is to be 55 fastened upon the holder. The inner surfaces of the junctures between said stem or

shank, *c*, and said prongs or projections, *d*, are rounded as at, *e*, to prevent any rough edges upon which the rope would be chafed. All the exposed surfaces of the device are 60 rounded for the same reason.

The preferred means of fastening a line of rope to this holder, is as follows: The end of a line of rope is passed between said prongs or projections, allowing it to rest 65 in the crotch between said prongs or projections, while the loose end of the rope, designated as *x*. In Figure 1 of the drawing, hangs to either side of said stem or shank, *c*. The rope is then passed around behind that 70 prong or projection which is opposite the side of the stem or shank over which the loose end of the line is suspended, also behind the other prong or projection and around over the loose end of the line of rope. 75 The part of the line which is being uncoiled, designated in Figure 1 of the drawing as, *y*, is then drawn taut. The line will be firmly secured to the holder, because of the friction exerted upon the line of rope 80 where it is wound about the prongs or projections and into the crotch between them, and also by the bight which the part, *y*, of the line, when taut, exerts upon the loose end of rope, *x*, as will be readily understood 85 by reference to the drawing. The line of rope is then followed to the next of the holders upon which it is to be secured. There, the line is passed from either side 90 around and behind both of said prongs or projections; thence it is looped between two said prongs or projections down into the crotch between them; thence around that one of the said prongs or projections around 95 which said line or rope was first passed. The line of rope is then drawn under the part of said rope which was first wound around the prong or projection. Thus, the line will be fastened to this holder in a manner similar to that by which the end of 100 the line of rope that was first secured to the other hook is engaged thereto. The part of the line which has been stretched will have a strong bight on the part of the line that is being stretched. In case there 105 is any slack in the part of the line which has been put in place, it will merely be necessary to pull the line taut upon the last holder upon which it was wound, as above described. The slack in the line may then 110 readily be taken up by pulling the other part of the line of rope. This operation is

then repeated for stretching successive parts of the line of rope to other of these holders. To remove the line from the holders, it is only necessary to pull the loose end of the line, frontwards and upwards from under the part, *y*, of the line, when the part of the line engaged by the holder is lifted free thereof.

It will be evident, that by the described use of this simple device, no knots are necessary in any part of the line to be stretched; that a line of rope may thereby be securely stretched between two or more of said holders; and that any slack in the line may be readily taken up, as described. This device results in a great convenience, both in stretching a clothes line into place, and in removing it from the holders. It will be noted that the construction of the holder, relative to the means for securing the same into place is such that the tension of and upon the line of rope which is stretched between any two of the holders is exerted more directly in the line of the screws or bolts whereby the holder is held in place against the side of a building, upright, or other means of support. By thus eliminating leverage upon the screws or bolts, the

possibility of the holders being pried away from the supporting member, and the consequent damage which may thereby result is to a great extent dispensed with.

I am aware that prior to my invention, clothes line holders have been made with upwardly extending, bifurcated projections or prongs. I, therefore, do not claim such a combination broadly, but I claim:

A hitching device for ropes, consisting of a single length of rod, bent in such wise that the ends thereof bifurcate from the portions of said rod contiguous with each of such ends, bent to extend about adjacent and parallel to each other in the same plane, at an acute angle relative to the plane of said bifurcating ends, and the remaining portion of said rod bent and fashioned into a loop with the opening and openings therebetween, substantially as illustrated and described.

In witness whereof, I have hereunto signed my name in the presence of two subscribing witnesses.

JOHN P. CUNNINGHAM.
